BICYCLE FENDER REFLECTOR

Frank P. Brilando and Rudolph L. Schwinn, Niles, Ill.,
assignors to Schwinn Bicycle Company, Chicago, Ill.

Filed Mar. 29, 1974, Ser. No. 456,283

Term of patent 14 years

Int. Cl. D10—06

U.S. Cl. D10—111

Fig. 1.

Fig. 2.

Fig. 3.

Fig. 4.

Fig. 5.

Fig. 6.

FIG. 1 is a front view of a bicycle fender reflector showing our new design;

FIG. 2 is a side view of FIG. 1;

FIGS. 3 and 4 are top and bottom views, respectively, of FIG. 1; and

FIGS. 5 and 6 are front and rear perspective views of the bicycle fender reflector.

A bicycle fender and bracket are shown in broken lines in FIG. 2 for illustrative purposes only.

We claim:

The ornamental design for a bicycle fender reflector, substantially as shown and described.
